Henry H. Young
ATTORNEY

UNITED STATES PATENT OFFICE

ALEXANDER PARKER, OF ETNA, CALIFORNIA

WATER ELEVATOR

Application filed September 12, 1930. Serial No. 481,410.

The invention relates to an elevator for lifting a fluid to a higher level, as water from a stream to a ditch or flume elevated thereabove.

5 A general object of the invention is to provide an improved and simplified elevator wherein the load-carrying elements comprise partition members upwardly movable as pistons in a lift passage and are carried by a continuous flexible conveyor.

A more specific object is to provide for positively bracing the pistons from the flexible conveyor which carries them and during their operative movement through the lift 15 passage.

A further object is to provide a piston-bracing means of the character described which permits the passage of the conveyor around sprocket wheels or the like, said 20 means applicable to continuous flexible conveyors generally.

Yet another object is to provide a water elevator of the class described which is particularly adapted for use in inclined lift 25 passages.

The invention possesses other objects and features of advantage, some of which, with the foregoing, will be set forth or be apparent in the following description of a typical embodiment of the invention, and in the accompanying drawing, in which,

Figure 1 is a partly sectional side elevation of an elevator embodying the invention and operably disposed.

35 Figure 2 is a sectional view at 2-2 in Figure 1.

Figure 3 is an enlarged fragmentary view at 3-3 in Figure 1.

40 Figure 4 is an enlarged fragmentary view at 4-4 in Figure 1.

Figure 5 is a section at 5-5 in Figure 3.

As particularly illustrated, the novel features of the present invention are incorporated in the structure of an elevator unit wherein wall members 6, 7, 8 and 9 cooperate to define a lift passage 11 of uniform cross-section. As shown in Figure 1, said unit is disposed to dispose the passage 11 in angular relation to the vertical, this disposal of the unit being that in which the same is utilized

in effecting the delivery of water from a stream 12 over a dyke or bank 13 bounding the same. Shafts 14 and 15 are journaled at opposite ends of the structure and mount rotary members 16 which cooperatively carry a continuous flexible conveyor 17 having a portion thereof longitudinally traversing the passage 11. Load-supporting piston members 18 are carried by the conveyor 17 for partitioning engagement in the passage 11 whereby they are arranged to raise water thereabove for discharge at the upper passage end, a discharge spout 19 being provided for effecting a directed delivery of the elevated water.

The conveyor 17, it will now be noted, comprises a pair of laterally spaced sprocket chains 21 of like length, and the members 16 are sprocket wheels for engaging the chains, wheels of like size being provided on each shaft. Said chains 21 are of a usual sprocket-chain structure wherein alternate elements 22 thereof comprise pairs of flat links 23 transversely spaced apart and pivotally connected to other chain elements 24 comprising pairs of flat links 25. Pivot pins 26 connect the successive said chain elements, and the links 23 overlap the links 25. A sprocket wheel 27 is mounted on the upper shaft 14 whereby the conveyor 17 is arranged to be operated by power derived from a suitable source (not shown).

Laterally opposite elements 22 of the two conveyor chains jointly carry the piston elements 18. As particularly shown, block members 29 are mounted on the said chain elements 22 to extend longitudinally thereof, and the pistons 18 are fixed to the leading ends of said blocks to extend transversely of the chain elements which carry them. The mounting of the blocks 29 is effected by fixing them to the links 23 of said elements 22, said links being formed with integral lateral extensions whereby to receive the blocks between the latter. The blocks 29 are mounted to extend solely from that chain side which lies radially outwardly of the sprocket wheels 16 as the chain moves therearound.

The chains 21 extend along the passage wall 8 in close adjacency thereto whereby the

pistons 18 extend transversely from the said wall and as partitions in said passage. As shown, these piston partitions comprise plates provided with anti-friction rollers 31 at the edges thereof which oppose the passage walls 6, 7 and 9, the plate being shaped to provide for a maximum degree of partitioning of the passage 11.

Since the weight of water being elevated by and above a piston 18 will tend to deflect said piston out of its transversely partitioning relation to the passage 11, means are provided for bracing such partition against deflection during its operativeness. As particularly shown, such means comprises the provision of brace blocks 32 mounted on the chain elements 22 which immediately succeed the piston, said blocks cooperating with the blocks 29 to provide brackets behind the piston which are effectively triangular, the various blocks being appropriately shaped. In the present instance, two blocks 32 are provided for bracing operation at each chain, and said blocks are mounted on the elements 22 which carry them in the same manner as are the blocks 29. In this manner, an appreciable length of conveyor chain is utilized as part of a bracket support for the piston, said chain length including a plurality of the pivotally related chain elements 22 and 24.

It is obvious that the reaction to the operation of the described sectional brace or bracket urges the chain portions thereat toward the passage wall 8, and means are provided to support the chain from said wall for movement therewith. Accordingly, and as shown, like members 33 are mounted on and between the opposite chain elements 22 which carry the brace blocks 29 and 32, said members carrying rollers 34 for engagement with the passage wall 8 whereby to slightly space the chains from said wall. In the present instance, the members 33 are provided with transverse end flanges 35 whereby they are arranged to be fixed to the elements 22 by use of the chain pins 26, the latter being of the necessary excess length for the purpose.

The now-described structure of the piston bracing means is seen to provide for a passing of the chains around the sprockets by permitting an angular separation of the various brace block sections, this feature being brought out in the showing of Figure 1 wherein block-carrying chain elements 22 are shown as engaging the upper sprocket 16. While the present specific disclosure particularly concerns an application of the piston bracing means to an overhanging wall of a water lift passage, the essential features thereof are understood as applicable in a conveyor lift passage which has vertical walls, or in a passage in which the piston bracing means is operative against a lower wall or a side wall. Furthermore, it is clear that the disclosed bracing means is advan-

tageously applicable to load-carrying elements of conveyor chains generally.

It is noted that in the present instance, the shafts 14 and 15 are journalled in lateral extensions 36 of the passage wall members 7 and 9 at opposite ends of said members. Track members 37 are mounted on and along the outer side of the wall member 8 for supporting engagement with the rollers 34 of the piston assemblies whereby the chains 21 may be supported between the sprocket wheels 16 and externally of the lift passage. In this manner, the structure shown comprises a self-contained elevator unit for installation where desired. In practice, the conveyor assembly would be driven at a speed to minimize the escape of water by the pistons, the need for the equivalent of piston rings thus being avoided.

From the foregoing description, taken in connection with the accompanying drawing, the advantages of the construction and method of use will be readily understood by those skilled in the art to which the invention appertains. While I have now described the principle of operation, together with the device which I now consider to be a preferred embodiment thereof, it is understood that the device shown is merely illustrative, and that such changes may be made when desired as fall within the scope of the appended claims.

Having thus described my invention, I claim as new and desire to secure by Letters Patent of the United States, the following:

1. In an elevator, means providing a lift passage of uniform cross-section, a continuous chain conveyor longitudinally traversing said passage adjacent a passage wall, a lift element carried by a link structure of said conveyor and transversely partitioning said passage for raising material thereabove therewith, and brace members directly carried by succeeding said link structures and cooperatively coactive between said lift element and said passage wall to support said lift element in fixed angular relation to said wall while the said lift element operates in said passage.

2. In an elevator for liquids, means providing a laterally closed lift passage of uniform cross-section, a continuous chain conveyor longitudinally traversing said passage adjacent a passage wall, sprocket wheels carrying said chain conveyor, a lift element carried by said conveyor and transversely partitioning said passage for raising material thereabove therewith, and brace members carried by succeeding said conveyor elements and cooperatively coactive between said lift element and said passage wall to support said lift element in fixed angular relation to said wall while the said lift element operates in said passage, successive said brace members arranged for an angular separation thereof

while the conveyor elements thereat engage a sprocket wheel.

3. In an elevator for liquids, a structure providing a laterally closed and steeply inclined lift passage of uniform cross-section, a continuous and flexible conveyor chain longitudinally traversing said passage adjacent the upper passage wall, sprocket wheels carrying said chain, a lift element carried by said chain and transversely partitioning said passage for raising liquid thereabove therewith, anti-friction means of the lift element operative between the different edges thereof and the passage walls, and a sectional bracket carried by said chain and operative behind said lift element during a working traverse thereof through said passage, different sections of said bracket fixedly related to different chain links and angularly separable when the chain is flexed between the said links for passing around a said sprocket wheel.

4. In an elevator, a chain conveyor, a load-carrying element extending transversely from said conveyor and carried by a chain link, and brace block members directly carried by said link and succeeding links of the chain, said blocks cooperative when said links are aligned to provide a bracket support for said element with respect to the chain and arranged to be angularly separated when said links are angularly related.

5. In an elevator, a continuous chain conveyor, a lift element carried by an element of said conveyor, and brace members carried by succeeding conveyor elements including said first conveyor element and cooperatively coactive between said lift element and the said conveyor elements to support said lift element in fixed angular relation to the line of said conveyor elements when the same are mutually aligned.

6. In a conveyor, a chain for one-way movement longitudinally thereof, a load-moving element carried by a link of the chain to extend transversely from the chain, and brace members carried by succeeding chain links and cooperatively coactive between said element and the various said links when the latter are mutually aligned to brace the element from behind and in fixed angular relation to the line of said links.

7. In a conveyor, a chain, means providing a fixed bearing surface adjacent and parallel to a working portion of said chain, a load-moving element carried by a link of the chain to extend transversely from the chain, and brace means directly carried by succeeding links including said first link and cooperatively coactive between said element and said bearing surface to brace the element from behind while the said links are mutually aligned.

8. In a conveyor, laterally spaced chains for simultaneous and like movements longitudinally thereof and having corresponding

portions thereof mutually coplanar, a load-moving element carried by and between opposite links of the chains to extend transversely from the plane of the chains thereat, and brace members carried by succeeding links of each chain including the links carrying said element, said brace members cooperatively coactive between said element and the links which carry them to brace the element from behind while the links carrying the sets of brace members are mutually aligned.

9. In conveyor apparatus, means providing a fixed and planar bearing surface, laterally spaced chains for simultaneous and like movements opposite said surface, a load-moving element carried by and between opposite links of the chains to extend transversely from the chains thereat, brace members carried by succeeding and corresponding links of each chain and cooperatively coactive between said element and the links which carry them to brace the element from behind and with respect to said links, tie members connecting corresponding said links of the different chains, and bearing means on said tie members for engagement with said bearing surface whereby said chains are held spaced from said surface.

10. In an elevator of the class described, a continuous chain conveyor, a series of brace blocks directly carried by a succession of the chain links, and a lift element fixed on the forward said brace block, said brace blocks cooperatively coactive between said lift element and the said chain links to support said lift element in fixed angular relation to the line of said conveyor elements when the same are mutually aligned.

11. In an elevator, means providing a fixed bearing surface, laterally spaced chains for simultaneous and like movements longitudinally thereof and having corresponding portions thereof mutually coplanar, a set of brace members directly carried by succeeding and corresponding links of each chain, a lift element fixed to and between the leading brace members of said sets thereof to extend transversely from the chains thereat, tie members connecting corresponding said links of the different chains and arranged for bearing engagement with said bearing surface, said tie members and brace members cooperative through said links to brace said lift element from said surface.

In testimony whereof I affix my signature.
